WALL MOUNTED DRINKING FOUNTAIN OR SIMILAR ARTICLE

Louis P. Benua, Columbus, Richard J. Radcliffe, Worthington, and William Taylor, Columbus, Ohio, assignors to The Ebcu Manufacturing Company, Columbus, Ohio, a corporation of Ohio

Filed Aug. 17, 1960, Ser. No. 61,793

Term of patent 14 years

(Cl. D67—4)

Fig. 1 is a perspective view of a wall mounted drinking fountain or similar article embodying our new design;

Fig. 2 is a front elevational view thereof;

Fig. 3 is a side elevational view thereof; and

Fig. 4 is a top plan view thereof.

The side opposite that shown in Fig. 3 is identical to the side shown in Fig. 3.

We claim:

The ornamental design for a wall mounted drinking fountain or similar article, substantially as shown and described.
